UNITED STATES PATENT OFFICE.

RUDOLF HÜRLIMANN, OF ST. GALLEN, SWITZERLAND.

SWITCH ARRANGEMENT FOR ELECTRIC-LIGHT INSTALLATIONS AND THE LIKE.

Application filed August 20, 1926, Serial No. 130,541, and in Switzerland October 30, 1925.

This invention relates to a switch arrangement for electric light installations and the like.

An embodiment of the invention is shown, 5 by way of example, in the accompanying drawing in which:—

Fig. 1 shows the switch arrangement consisting of a switch and of an operating mechanism positively connected with the switch 10 and working without current.

Fig. 2 is a section through the switch on line A—A of Fig. 3.

Fig. 3 is a cross section of the switch.

Fig. 4 shows in section one of the operating 15 mechanisms for the switch.

The switch arrangement comprises a switch 1, which has a casing with lid, in which casing a feed disk 2 is keyed on an axle 2^a. The axle 2^a is pivotably mounted in the bottom plate of the casing and carries on its upper end a contact block 15^a. The disc 2 has a groove 23 and cams 24. In the groove 23 pull-elements 12 are located which are attached at one end to a common pin 3 designed 20 to engage behind one of the cams 24 of disk 2. The pull elements 12 are guided in the switch casing each over a pulley 8, 9. A spiral spring 4 is attached to the pin 3 and fixed at its other end to the casing. This spiral 25 spring 4 has the tendency to pull towards it the pin 3 with the pull elements. The contact block 15^a is rotatable between two contact springs 13, 14 of terminals 6, 7; insulating pieces 15 being fixed in two opposite sides 30 of said contact block. When the axle 2^a is rotated the contact surfaces and the insulating surfaces 15 of the contact block are alternately brought into contact with the contact springs 13, 14 so that the circuit is closed 35 and interrupted.

The pull elements 12 are preferably enclosed in flexible tubes 22 and connected each to an operating mechanism 16 which works without current. Each operating mechanism 40 comprises a casing 25 closed by a lid 26. On a bracket 21 in said casing a two armed lever is pivotably mounted which is composed of the arms 19^a and 19^b. To the horizontal arm 19^b a spiral spring 20 is attached the other 45 end of which is fixed on the bottom plate of the casing. The spring 20 tends to pull the arm 19^b towards the bottom plate of the casing, the arm 19^b being thus pressed against a shaft of a push 10. This push 10 is controlled by a spring 17 and located in a bore 50 of lid 26. The spring 17 is enclosed between

a plate 27 which closes the bore in the lid and a collar on the shaft of push 10. This spring 18 pushes the shaft of the push 10 upward in the direction of the arrow. To the arm 19^b 60 the end of one of the pull elements 12 is attached after it has been guided around a pulley 18. The flexible tubes 22 enclosing the pull elements are fixed in convenient bores in the walls of the casing of the switch end 65 of the casing 25.

The switch mechanism operates as follows. If the push 10 is depressed against the action of the spring 17 the two-armed lever 19^a, 19^b is oscillated. The pull element 12 attached 70 to the arm 19^b of the lever is pulled so that the feed disk is rotated of a quarter revolution, the spring 4 being put under tension at the same time. As soon as the push 10 is released the springs 20, 17 of the operating 75 mechanism make the elements 10, 19^a, 19^b return into their initial positions. The spring 4 can expand and moves the pin 3 until it grips behind the next following cam 24 of the disk 2^a, the pull element 12 being pulled 80 by said pin. If one of the operating mechanisms 16 is operated again a quarter revolution of the disk 2^a is caused so that the circuit, in which the terminals 6, 7 are inserted 85 can be interrupted and closed at once.

With one switch a great number of operating mechanisms 16 may be connected by means of pull elements, these operating mechanisms being mounted at different places and at any desired distance from the switch. 90 Owing to the operating mechanisms working without current no electric cables are required the pull elements being substituted for the same which cost less.

In many cases no flexible tubes will be required, in which case the pull elements are merely guided over pulleys, if however the flexible tubes 22 are used the pull elements may be guided by spherical elements 11 of known type at the points where the direction of the pull elements has to be altered.

The switch arrangement is specially adapted for staircase lighting, or in all cases where one or several electric switches have to be operated from different points.

I claim:—

1. An electric rotatable switch, comprising in combination a central switch axle, a notched disc on said shaft, a transverse pin adapted to act upon the teeth of said notched disc, a pull spring holding said transverse pin in its inoperative position, a number of

currentless switch boxes, a push button in each switch box, a pull element from each switch box attached to said transverse pin, and an intermediate element for exerting a pull upon said pull element at the depression of the corresponding push button to make said transverse pin impart a part rotation to said notched disc.

2. An electric rotatable switch, comprising in combination a central switch axle, a drum on said axle said drum having four pairs of teeth, a transverse pin bearing against one of said pairs of teeth, a pull spring attached at the one end to said transverse pin and at the other end to a stationary point for holding said transverse pin in the inoperative posi-

tion, a number of pull strings attached to said transverse pin, rollers guiding said pull strings, currentless wall boxes one for each pull string, a spring-controlled push button 20 in each wall box, an elbow lever pivotally mounted on each wall box said push button adapted to act upon one arm of said elbow lever, one end of the corresponding pull string, attached to the other arm of said elbow lever, a spring for pulling said first mentioned arm of said elbow lever against said push button, and a sheath for each pull string.

In testimony whereof I affix my signature.

RUDOLF HÜRLIMANN.
